US0D1111841S

(12) **United States Design Patent** (10) Patent No.: **US D1,111,841 S**
(45) Date of Patent: ** Feb. 10, 2026

(54) **BOTTLE**(71) Applicant: **H.J. Heinz Company Brands LLC**,
Pittsburgh, PA (US)(72) Inventors: **Michelle Marie Hayden**, San
Francisco, CA (US); **Peter Brian
Clarke**, Newtown, CT (US); **James E.
McCay**, Fairfield, CT (US); **Sean
Evelich**, Hamden, CT (US); **Trond
Erik Tollefson**, London (GB)(73) Assignee: **H.J. Heinz Company Brands LLC**,
Pittsburgh, PA (US)(**) Term: **15 Years**(21) Appl. No.: **29/939,481**(22) Filed: **Apr. 26, 2024****Related U.S. Application Data**(60) Division of application No. 29/813,963, filed on Nov.
2, 2021, now Pat. No. Des. 1,030,493, which is a
continuation-in-part of application No. 29/809,075,
filed on Sep. 24, 2021, now Pat. No. Des. 1,043,348.(51) LOC (15) Cl. .... **09-01**(52) U.S. Cl. .... **D9/575**(58) **Field of Classification Search**USPC D9/522, 530, 531, 538, 542, 549, 558,

CLAIM

The ornamental design for a bottle, as shown and described.

DESCRIPTION

FIG. 1 is a top, front perspective view of a bottle in accordance with a first embodiment of our new design;

FIG. 2 is a bottom, rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, front perspective view of a bottle in accordance with a second embodiment of our new design;

FIG. 10 is a bottom, rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a top, front perspective view of a bottle in accordance with an eleventh embodiment of our new design;

FIG. 18 is a bottom, rear perspective view thereof;

FIG. 19 is a front elevation view thereof;

FIG. 20 is a rear elevation view thereof;

FIG. 21 is a right side elevation view thereof;

FIG. 22 is a left side elevation view thereof;

FIG. 23 is a top plan view thereof; and,

FIG. 24 is a bottom plan view thereof.

The broken lines in the figures show portions of the bottle that form no part of the claimed design. The dash-dot lines indicate an unclaimed boundary and form no part of the claim.
